OTTO PETERMANN, OF GROTON, NEW YORK, ASSIGNOR TO CORONA TYPEWRITER COMPANY, INC., OF GROTON, NEW YORK, A CORPORATION OF NEW YORK.

TYPEWRITING-MACHINE.

1,356,826.

Specification of Letters Patent. Patented Oct. 26, 1920.

Application filed June 5, 1917. Serial No. 172,854.

To all whom it may concern:

Be it known that I, OTTO PETERMANN, a citizen of the United States, and resident of Groton, county of Tompkins, and State 5 of New York, have invented certain new and useful Improvements in Typewriting-Machines, of which the following is a specification.

This invention relates more particularly 10 to key actions of front-strike, visible typewriting machines.

One of the principal objects of the invention is to provide a key action which has a very easy and uniform touch and 15 in which the type bars have an upward and rearward accelerated movement.

Another object of the invention is to so construct the key action that it will form an efficient rebound lock to effectively 20 hold the type bar against any rebounding motion after the bar has returned to its point of rest. By providing an effective rebound lock any form of noiseless cushioning material may be used as a stop to receive the blow or impact of the type bar 25 on its return from its printing movement. In typewriting machines which are not provided with a rebound lock the type bars frequently so move in rebounding from the 30 type rest that when adjacent type bars are actuated in succession they are liable to interlock.

Another object of the invention is to provide simple means for adjusting the various 35 parts of the type bar action and to dispense with the usual form of turn buckle adjustment between the key lever and the type bar.

Other objects of the invention are to 40 provide a simple and efficient key action in which substantially all the parts may be punched from sheet steel or other suitable material; to provide means whereby the parts of the key action may be readily made 45 and assembled, and to provide a key action occupying a minimum amount of space to thereby particularly adapt it for small portable typewriting machines.

In the drawings, Figure 1 is a side elevation 50 of a key action, the supporting parts and the platen being shown in sectional view;

Fig. 2 a similar view showing the type bar in its printing position against the 55 platen;

Fig. 3 a view similar to Fig. 1, showing a slightly modified form of bell-crank lever interposed between the key lever and the type bar;

Fig. 4 a detail sectional view showing 60 the manner of mounting the bell-crank lever in its supporting bar;

Fig. 5 a detail plan view of the modified form of bell-crank lever shown in Fig. 3;

Fig. 6 a detail view of a portion of the 65 key lever;

Fig. 7 a diagrammatic view illustrating the acceleration of the type bar;

Fig. 8 a detail side view of a portion of the bearing segment, showing one of the 70 fulcrum prongs in section and showing a slightly varied form of bell-crank lever;

Fig. 9 a bottom plan view of the bell-crank lever shown in Fig. 8;

Fig. 10 a detail view showing the manner 75 of assembling the bell-crank lever shown in Figs. 8 and 9; and

Fig. 11 a fragmentary plan view of a key action for operating a type bar at the left hand side of the machine; 80

Fig. 12 a view similar to Fig. 1, showing a key action for a type bar located at the right hand side of the machine; and

Fig. 13 a fragmentary vertical sectional view on the line XIII—XIII of Fig. 11. 85

Referring to the various parts by numerals, 1 designates the platen which may be supported on any suitable form of carriage; 2 the type bar segment which forms the support for the type bars, said support being of any suitable form or construction, and 3 the type rest, said rest being provided with a suitable soft cushioning material 4. The type bar 5 is mounted at its rear end upon a pivot 6, and carries 95 at its forward end a type head 7, which, as shown in the drawing, is provided with three printing characters. Below the type bar, near its rear end, is suitably supported the key lever fulcrum bar 8, said bar being preferably located close to the lower edge of the type bar in order that the key action will occupy a small space and be adapted for use in small portable typewriting machines. The key lever 9 is 105 notched on its under side at its rear end, as at 10, to receive the edge of the fulcrum bar, as shown clearly in Fig. 1. The fulcrum bar is perforated to admit of the passage of the rear end of the key lever. 110

- The forward end of the key lever extends upwardly and is provided with the usual finger key 11. Near its forward end the key lever is provided with an upwardly 5 extending vertical part 12 which is adapted to engage the under side of a cushioning bar 13, the said bar limiting the upward movement of the key lever and holding said lever in its normal or at-rest position.
- 10 The upper end of the vertical portion 12 of the key lever is bent laterally to form a stop lug 12^a, said lug being adapted to be bent vertically in order to adjust the at-rest position of the key lever. Extending 15 rearwardly from the part 12 is a bendable, substantially horizontal adjusting prong 14. To the forward end of this prong is pivoted an upwardly extending link 15.
- 20 A bell-crank lever 19 is pivoted on an upwardly extending fulcrum prong 17 formed integral with a sheet metal segment 18. The fulcrum prong is in the form of a twisted tooth integral with a flange on the sheet 25 metal segment. The bell-crank lever 19 is formed with an upwardly and forwardly extending arm 19^a, and with a rearwardly extending arm 19^b. The arm 19^b is greater in length than the arm 19^a and said arm 19^b 30 extends rearwardly in a substantially horizontal line.

It will be observed that the fulcrum-support 35 is in the form of a sheet-metal bar of channel form, the two longitudinal edges flanges extending upwardly, one of them being deeper than the other in order to afford sufficient metal to form the upstanding ears 17, these ears being formed by vertically slitting the flange at intervals and twisting 40 the lugs thus formed so that they will lie at an angle with reference to the supporting-bar. This results in a stiff and light fulcrum-bar which can be manufactured at a minimum cost and which will have the minimum weight.

The rear end of the type bar is formed with a short downwardly extending arm 23, and said arm is connected to the arm 19^b of the lever 19 by a horizontal link 24. The 50 points of connection between the arm 23, link 24 and arm 19^b of the bell-crank lever, are in a direct line with the center of the pivot 22 of said lever when the parts are in their normal at-rest position, as shown clearly 55 in Fig. 1. When the parts are in the position just described the type bar can not be moved upwardly except through a downward movement of the key lever. Any tendency of the type head to move upwardly is prevented by 60 the arm 23, link 24 and lever arm 19^b because the forward thrust of the arm 23 will be transmitted directly to the center of the pivot 22 of the lever 19 and there will be no upward movement of the type bar. These 65 parts are on centers and are locked against

movement through the type bar. It is manifest that this will effectually prevent any rebound of the type bar after it has moved back to its at-rest position. Connected to the bell-crank lever and the key lever fulcrum 70 bar is a spring 25 which returns all the parts to their normal at-rest positions upon the release of the key lever. 26 indicates a universal bar of any suitable construction and which is adapted to be engaged by the key 75 lever as it is depressed.

The upwardly extending fulcrum prong 17 supporting the lever 19, may be readily bent forward or rearward by any suitable device, in order to properly adjust the connection between the rearwardly extending arm 19^b of the lever 19 and the forward end 80 of the link 24. By providing this bendable fulcrum prong proper adjustment may be made between the lever 19 and arm 23 of the type bar without the necessity of using any other form of adjusting device, such, for instance, as the ordinary and well-known turn buckle. In order to secure the proper adjustment between the key lever, the link 15 and the arm 19^a of the bell-crank lever, the prong 14 of the key lever is bendable vertically. It is, therefore, to be noted that all of the necessary adjustments between the several parts of the key action may be secured by bending suitably arranged lugs or 85 prongs, thereby avoiding the use of screws or other similar devices which are liable to be jarred out of proper adjustment in the use of the machine. This method of adjusting is especially advantageous in securing the proper positions of the parts to lock the type bar against rebound.

In Fig. 2 the key action is shown as having been operated to throw the type head on the type bar to the printing point on the platen. It is manifest, therefore, that as the key lever is depressed the motion transmitted to the type bar will be greatly accelerated toward the completion of the printing movement. It is also manifest that at the start of the key lever movement the type bar movement will be slow but will respond to a very light touch. By reason of the disposition of the link 24 and arm 19^b of the bell-crank 105 lever 19 there must be a slight movement of the lever 19 before there can be any upward and forward movement of the link 24. This also contributes to the ease of the key action.

By reason of the arrangement of the arm 19^b of the bell-crank lever, the link 24 and the arm 23 of the type bar, the type bar will be given an accelerated movement toward the platen. It is manifest that as the arm 19^b moves upwardly and forwardly, its 110 travel away from the pivotal point of the type bar is accelerated, and that consequently the type bar will be given the described accelerated movement. It is clear, therefore, that the acceleration of the type 115

120 125 130

bar will be due to the upward and forward movement of the arm 19^b of the said lever. By reason of this construction and arrangement of the parts the key stroke may be 5 made reasonably short.

In the drawings the movements of the type bar, the bell-crank lever and the key lever, are indicated by numerals and dotted lines. The downward movement of the key 10 lever is indicated by the numerals 0, 1, 2, 3 and 4, the horizontal lines adjoining said numerals indicating equal parts of the downward travel of the said lever. The upward movement of the type bar is indicated by the 15 numerals 0, 1, 2, 3 and 4, the spaces between said numerals indicating the distances traveled by the type bar during the movement of the key lever through the spaces between corresponding numerals. In Fig. 7 the acceleration of the type bar movement by reason of the peculiar arrangement of the bell-crank lever, is diagrammatically illustrated. The movement of the bell-crank lever is 20 divided into four parts to correspond to the numerals 0, 1, 2, 3 and 4, the spaces between said numerals indicating the divisions of the movements of the key lever and the type bar. The corresponding positions of the short arm 23 of the type bar are also indicated in this figure. It will be 25 readily seen that the type bar will receive a very slight movement during the first quarter of the upward movement of the arm 19^b of the bell-crank lever. It will also be observed that the upward movement of the arm 23 of the type bar is gradually increased 30 during the successive quarters of the movement of the said arm 19^b, the greatest travel being during the last quarter of said movement. It is manifest, therefore, that the upward movement of the type bar corresponding to the downward movement of the key between the numerals 0 and 1, is very 35 much less than the upward movement of the type bar corresponding to the downward movement of the key between the numerals 1 and 2; and that the greatest movement of 40 the type bar results from the downward movement of the key between the numerals 3 and 4.

It is manifest that the locking action between the type bar, link 24 and bell-crank lever 19, may be secured by arranging the 45 point of connection between the link 24 and the arm 19^b slightly below a direct line drawn between the center of the pivot 22 of the bell-crank lever and the point of connection between the rod 24 and the arm 23 of the type bar. This arrangement of the parts, while effective, will require a slightly greater lost motion in the bell-crank lever 50 before the movement thereof will actuate the type bar. While the parts in this position will be slightly off centers, it will, of course, be understood that the same result of locking the type bar against rebounding 55 will be secured.

In Fig. 3 a slightly different form of bell-crank lever is interposed between the vertical link 15 and the horizontal link 24. As shown in this figure and in Fig. 4, the bell-crank lever 27 is formed with an arch-shaped bearing lug 28 which is formed integral with the body of the lever at the pivotal point thereof so that the said lever has two points of support and bearing on the pivot rod, as shown clearly in Fig. 4. The 70 fulcrum segment 29 is provided with upwardly extending bearing lugs 30 between which the slots 31 are formed. These slots are broad enough to receive the body portion of one bell-crank lever and the bearing 75 lug of the adjoining bell-crank lever, as clearly shown in Fig. 1. By this arrangement the bell-crank levers are held accurately on their pivotal supports and all tendency to twist or cant is avoided. The 80 operation of the key action provided with a bell-crank lever as shown in Fig. 3, is precisely the same as the construction shown in Fig. 1.

In Figs. 8, 9 and 10, the bell-crank lever 90 is provided with a rigid pivot 32, which is adapted to fit a corresponding aperture in the fulcrum prongs. Each bell-crank lever is provided with a rigid pivot so that each may be independently assembled and adjusted. The arch-shaped bearing lug is adapted to be bent close to the side of the fulcrum prong, as shown in Fig. 8, to maintain the bell-crank lever in place. The free arm of the arch-shaped bearing lug extends 95 outwardly away from the pivot, as shown in Fig. 10, to facilitate the assembling of the parts. When the pivot is in place in the fulcrum prong, the free arm or member of the arch-shaped bearing lug is bent inwardly 100 to the side of the fulcrum prong, as shown in Fig. 8. Any one of the bell-crank levers may be readily detached from its fulcrum prong by bending outwardly the free arm of the arch-shaped lug. This permits the 105 parts to be readily assembled and also readily detached from the bearing segment. The pivot 32 is sufficiently long to extend through the fulcrum prong and into an aperture 33, formed in the free arm of the 110 arched bearing lug so that each bell-crank lever will have two points of connection to the pivot in its assembled operative position, one at each side of the bearing prong.

What I claim is:

1. In a key action the combination of a type bar, a key lever formed with a vertically extending part near its forward end, a laterally bent vertically adjustable lug on said vertical part adapted to engage a key 125 lever stop, a rearwardly extending bendable prong formed on said vertical extending part, a bell-crank lever, a link connected to the bendable prong on the key lever and to one arm of the bell-crank lever, and a link 130

- connecting the other arm of the bell-crank lever to the type bar.
2. In a key action, the combination of a type bar, a key lever having an integral upwardly extending and laterally bendable stop lug, a key lever stop adapted to be engaged by the bent upper end of said stop, a bendable finger formed on said key lever, a bell-crank lever fulcrumed above the key lever, a vertical link connecting one arm of said bell-crank lever with the free end of said bendable finger, and a link connecting the other arm of said bell-crank lever with the type bar.
- 10 3. In a key action, the combination of a pivoted type bar, a key lever pivoted at its rear end, a bell-crank lever, an adjustable pivotal support for the bell-crank lever, an

adjustable connection between the key lever and one arm of the bell-crank lever, a link 20 connecting the type bar with the other arm of said bell-crank lever, a fixed stop above the key lever, an adjustable stop carried by the key lever adapted to engage said fixed stop to limit the upward movement of the 25 free end of the key lever, and a spring for normally holding said adjustable and fixed key lever stops in engagement with each other and for normally maintaining the point of connection between the link and bell-crank lever on a line with the pivotal point of the bell-crank lever and the point of connection between the link and type bar. 30

This specification signed this twenty-fourth day of May, A. D. 1917.

OTTO PETERMANN.
